FOLDING CLOTHES RACK OR SIMILAR ARTICLE

Raymond H. Ovendale, San Gabriel, Calif.
(1614 Chestnut St., Alhambra, Calif.)

Filed June 4, 1962, Ser. No. 70,411

Term of patent 3½ years

(Cl. D80—8)

FIG. 2.

FIG. 3.

FIG. 1 is a perspective view of a folding clothes rack or similar article embodying my new design;

FIG. 2 is an elevational view taken from the end opposite that shown in FIG. 1; and

FIG. 3 is an elevational view taken from the end opposite that shown in FIG. 1, with the rack in a folded position.

I claim:

The ornamental design for a folding clothes rack or similar article, substantially as shown and described.
